UNITED STATES PATENT OFFICE.

JAMES I. AYER, OF CAMBRIDGE, MASSACHUSETTS, ASSIGNOR TO SIMPLEX ELECTRIC HEATING COMPANY, OF CAMBRIDGE, MASSACHUSETTS, A CORPORATION OF MASSACHUSETTS.

FLEXIBLE ELECTRIC HEATER.

1,192,153.

Specification of Letters Patent. Patented July 25, 1916.

Application filed August 14, 1913. Serial No. 784,731.

To all whom it may concern:

Be it known that I, JAMES I. AYER, a citizen of the United States, and resident of Cambridge, county of Middlesex, State of Massachusetts, have invented an Improvement in Flexible Electric Heaters, of which the following description, in connection with the accompanying drawings, is a specification, like letters on the drawings representing like parts.

This invention relates to electric heating apparatus, and more particularly to a flexible and portable electric heater, having a protecting armor thereon, and capable of use as a footwarmer or the like. I form such heater of any suitable electrical heating element, preferably as a spirally wound electrical resistance upon a core of asbestos or the like, and cover the same with fire-proofing material, applying to such fire-proofing material a flexible protecting armor. This flexible covering may be in the form of a metallic ribbon, wound spirally about the heating element incased in its fire-proofing material, or may be in the form of a wire or flexible tubing, so long as sufficient protection is secured and the flexibility of such covering and of the heater as an entirety is maintained. This metallic protection prevents injury to the heater when used as a foot warmer, and enables it to bear any weight which is apt to be placed upon it in use. Having provided the heating element with its metallic protecting covering as above explained, I then take a suitable length of the heater to provide sufficient heat radiation as may be needed, form the same in a coil or other shape, and cover the coil so formed with carpet, canvas, or any suitable fabric, so that it presents an attractive appearance as a rug or mat. The heater so formed, being flexible, portable, and with its metallic protecting covering to prevent injury to the electrical resistance, and its textile covering for appearance, finish, and wear, may be advantageously employed in a variety of uses, such as a foot warmer under a desk, adjacent an arm chair, in an automobile or in the sick-room, being connected to any suitable source of electrical current supply.

Other features of the invention, novel combinations of parts, and details of construction will be hereinafter more fully pointed out and claimed.

Referring to the drawings, illustrating a preferred embodiment of the invention, Figure 1 illustrates an embodiment of the invention in a preferred form, having a portion of the textile covering broken away; 60 Fig. 2 is a view of another form of mat, wherein the heating coil is laid in reflex form; Fig. 3 is a fragmentary cross sectional view of my flexible electric heater; Fig. 4 is a view illustrating one form of the metallic 65 protecting armor; and Fig. 5 is a view illustrating the electrical heating element as formed upon a core and embedded in the fire proofing material.

While I have illustrated herein two forms 70 of mats or rugs, one showing the electric heating element in the form of a flat coil, and the other in a relatively long and narrow form with the heater coiled in reflex manner, I wish it understood that I am not 75 limited in any way to these two forms, as the invention, broadly considered, comprises any flexible electric heater, having some protecting material, preferably metallic, to prevent injury to the heating element, and the 80 entire heating coils being covered or inclosed within a suitable finishing material, preferably fabric.

As illustrated in the accompanying drawings, I apply to a suitable core 1 of asbestos 85 or other equivalent fire proof or insulating material, an electrical resistance in spiral form to provide the heating element, as indicated at 2, and then cover this electrical heating element with a covering of asbestos 90 3, again covering the asbestos with a metallic armor, such as the metal ribbon 4, wound in a spiral manner upon the covered core so prepared. Instead of the flat metallic ribbon 4 I may employ a spirally wound 95 wire or a flexible metal tubing to provide protection and retain the flexibility of the heater. By means of the spiral formation around a core of suitable diameter, as well as the spirally wound armored covering, I 100 am enabled to provide any length of such flexible electric heater, as indicated at 5, Figs. 1 and 2, as may be desired, to be made up into a rug or mat of any size or form to produce any desired extent of heat radiation. As shown in Fig. 1, I coil a suitable length of the flexible electric heater formed preferably as above explained into a round, flat mat of desired diameter, and cover the same with fabric 6, and 7, uniting the various 105 110

adjacent coils 5 to the fabric 6 by wire loops 8, or other suitable means. As illustrated in Fig. 3, I preferably alternate the wire loops 8 from one coil to the top fabric 6, and then 5 about an adjacent coil to the lower fabric 7, and so on alternately, thus uniting both fabric surfaces 6 and 7, and retaining the mat in proper shape. At the meeting edges 10 of the fabric 6 and 7, fastening devices 9 may be utilized, or a line of stitching may be employed. Any other suitable means of holding the coils of the flexible heater 5 in proper shape may be employed, the usual buttons and stay cords, as used in upholstery being feasible.

In Fig. 2 I have illustrated a length of mat or rug with but comparatively little heat radiation, the successive coils of flexible heater 5 being spaced apart somewhat, 20 to reduce the heat power for a given area of mat. In this form, if the adjacent coils of the flexible heater are spaced a substantial distance apart, it may be desirable to fill in between the same with additional fabric 25 or filling, in order to present a smooth exterior to the textile fabric, carpet, or the like covering the same.

In both forms of mats illustrated in Figs. 1 and 2, I arrange the terminals 10 and 11 30 for the heating element at adjacent points on the side or end of the mat, where it may be readily connected to or disconnected from any suitable source of current supply.

While I have illustrated in preferred 35 form, my flexible heater as comprising a round core with the heating element wound in spiral form thereon, and with the fireproofing material and the metallic protecting covering also in round form, constituting 40 the circular flexible heater 5, it is of course within the scope of the invention to make the heater of any form desired, such as rectangular, elliptical, or otherwise in cross section.

An important characteristic of my pres-

ent invention is that a flexible electrical 45 heater is provided with suitable flexible armor, so that it can be wound or coiled into any shape or form, depending upon the uses to which it is put. By having the electrical heating element upon a core of suitable 50 diameter, flexibility is attained without danger of injury to the heating element, and the form in which such a flexible heater may be made up for use varies with the purposes to which such a heater is to be put, 55 and therefore almost any shape or form of mat, rug, or heating device can be made therefrom. The heater so made is of course portable from place to place, and from one source of current supply to another, the 60 flexibility of the entire heater adapting it for use in many places where other heating apparatus would be ineffective.

Having described my invention, what I 65 claim as new and desire to secure by Letters Patent is:

As an article of manufacture, an electrically heated rug, foot-warmer, or the like, comprising a flexible electrical heating element arranged as a flat but coiled form, 70 an outer textile covering of suitable form and size for a rug, foot-warmer, or the like, and adapted to inclose the electrical heating coils, a fireproofing substance between said electric heating element and said outer textile covering, a flexible protecting armor for the electrical heating element, and means to hold the coils of the electrical heater and the outer textile covering in desired shape and form.

In testimony whereof, I have signed my name to this specification, in the presence of two subscribing witnesses.

JAMES I. AYER.
